(57) CLAIM

The ornamental design for a brush pen, as shown and described.

DESCRIPTION

FIG. 1 is a front and bottom perspective view of a brush pen, showing my new design;

FIG. 2 is a rear and top perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof; and,

FIG. 9 is a perspective view thereof, shown in a used condition.

The broken lines shown in the drawings illustrate portions of the brush pen that form no part of the claimed design.
